UNITED STATES PATENT OFFICE.

ALEXANDER D. CLARKE, OF NEW YORK, N. Y.

ORE-CONCENTRATOR.

SPECIFICATION forming part of Letters Patent No. 276,775, dated May 1, 1883.

Application filed January 13, 1883. (No model.)

To all whom it may concern:

Be it known that I, ALEXANDER D. CLARKE, of the city, county, and State of New York, have invented a new and Improved Ore-Concentrator, of which the following is a full, clear, and exact description.

The object of my invention is to provide a new and improved device for concentrating ore in placer-mining by washing off and removing the particles of sand, &c.

The invention consists in an ore-concentrator constructed with a screen upon which the sand containing the ore is conducted, a series of settling-boxes into which the water passes after having passed through the said screen, and a flume arranged below the said screen, into which flume the water is conducted after having passed through the settling-boxes.

The invention also consists in various parts and combinations of the same, as will be fully described and claimed.

Reference is to be had to the accompanying drawings, forming part of this specification, in which similar letters of reference indicate corresponding parts in all the figures.

Figure 1 is a plan view of my improved ore-concentrator for placer-mining. Fig. 2 is a longitudinal sectional elevation of the same on the line $x-x$, Fig. 1. Fig. 3 is a cross-sectional elevation of the same on the line $y-y$, Fig. 1. Fig. 4 is a longitudinal sectional elevation of part of the same on the line $z-z$, Fig. 1.

An endless-belt screen, A, composed of a series of perforated plates or wire-netting sections hinged to each other, is passed over two polygonal rollers or drums, B B, pivoted in two walls, C C, between which the endless-belt screen is located. The rollers are so arranged that the endless-belt screen will be slightly inclined from its rear toward its front end, as shown in Fig. 2. An apron, D, is arranged between the two layers of the endless-belt screen, and is about parallel with the same—that is, it is inclined from the rear toward the front end, which front end rests upon a transverse gutter, E, resting on or projecting over the adjoining sides of two boxes, F, at the sides of, parallel with, and below the endless-belt screen A. Between the two boxes F a flume, G, is arranged, which is inclined from the rear toward the front end, and is below

the endless-belt screen. The boxes F are provided in the bottoms of their front ends with longitudinal openings or slots a , which can be closed by vertically-movable gates H, and at the bottoms of the front ends of the said boxes spouts H' project, as shown. The bottom J of each box F is inclined upward at an angle of about twenty degrees from the front end toward the rear end of the box. Each box is provided on the inner surface of its sides, at the upper ends, with inwardly-projecting flanges or brackets F', for supporting a screen, K, made of perforated metal plates, wire-netting, or other suitable material. Behind each box F a box, L, of the same height and width, is formed, which is provided on the inner surfaces of its sides, at the top of the same, with inwardly-projecting flanges or brackets K', for supporting amalgamated plates M M, which are inclined about the same as the bottoms J of the boxes F. An amalgamated plate, M, also rests on the upper end of the inclined bottom J, as shown in Figs. 1 and 4. The rear ends of the boxes L are connected by a large transverse box, N, from the front of which the flume G extends to the front end of the entire apparatus, as shown in Fig. 2. Cages O, made of rods, bars, or slats, or other suitable material, are arranged and held transversely in the rear ends of the boxes L, and are filled with sage-brush, grass, bushes, hay, or other material, through which water can filter. Like cages, O', filled in like manner, extend diagonally from the rear ends of the boxes L to the corners of the transverse end box, N, as shown in Fig. 1. Vertical guides b are attached on the inner surfaces of the front and rear walls of the transverse end box, N, which guides are arranged on each side of the rear end of the sluice or flume G, and are adapted to receive vertical gates for cutting off the communication of the flume with one or the other of the boxes arranged at the sides of the flume. Water-pipes P, arranged at each side of the flume, project from the inner surface of the front end wall of the box N into the said box, the ends of the said pipes being open for the passage of water from the box N to wash out the gold on the spout H', as herein-after more fully set forth. The pipes then extend forward on the outer surface of the inner

sides of the boxes L and F to the front ends of the boxes, and have their ends P' bent rectangularly to extend across the front ends of the boxes F, which ends P' of the pipes are 5 perforated. The pipes P are arranged at about half the height of the boxes L and F. A steep chute, Q, extends from the front end of the endless-belt screen A down into the front end of the flume G. A sliding gate, R, which is of 10 the width of the transverse gutter E, rests in the same, and is inclined upward from both ends toward the middle, so that it will be double-wedge-shaped. The water containing the sand, gold, &c., is conducted upon the endless-belt screen A by a flume, S, which can be 15 adjusted to have its lower end a greater or less distance from the front end of the upper layer of the endless-belt screen. Instead of using a movable endless-belt screen, a fixed 20 screen can be used. If the movable endless-belt screen is used, some suitable motor must be provided for rotating the rear drum, B, in such a manner that the belt can move in the direction of the arrow a', as shown in Fig. 2.

25 The operation is as follows: The sand, gravel, water, &c., containing the gold is conducted upon the screen A by the chute S. Accordingly, as a greater or less quantity of sand or gravel is carried by the water through 30 the chute S upon the screen A, the said chute is adjusted to have its lower end a greater or less distance from the front end of the screen A—that is, if the water contains a great quantity of sand and gravel, the chute must be ad- 35 justed to have its lower end at the rear end of the screen A, so that the sand, &c., may remain a longer time on the screen; but if the water contains but very little sand or gravel the lower end of the chute must be adjusted to be 40 near the front end of the screen. The water rushing through the chute S carries the sand and gravel toward the lower or front end of the screen, where the same accumulates when the stationary screen is used, and is drawn or 45 shoveled into the chute Q. If an endless-belt screen is used, as shown, the movement of the belt-screen carries the sand and gravel remaining on the same toward the lower end of the screen and dumps it into the chute Q.

50 The larger particles of sand, &c., remain on the screen, and the finer particles are washed through the same upon the apron D, and are washed by the water, which also passes through the screen upon the said apron into the trans- 55 verse gutter E. Accordingly, as the water is to be conducted from the gutter E into the box F on one side or the other of the screen, the sliding gate R is pushed to one end or the other of the said gutter E. As shown in Fig. 60 3, the water is to be conducted from the gutter E into the right-hand box F, and for this purpose the wedge-shaped gate R is moved to the left-hand end of the gutter E, so that the water and sand dropping from the end of the 65 apron D is deflected and guided toward the right by the right-hand inclined side of the wedge-shaped gate R. By moving the ad-

justable gate R to the other end of the gutter E, the water, &c., can be conducted to the left-hand box F. The water passes from the end 70 of the gutter E upon the screen K, which catches the larger particles of sand, &c. The gate H of that box F, into which the water passes, is closed, and the water accumulates in the box until it passes over the upper end of 75 the inclined bottom J into the box L, thence through the opening in the box N, the gate being open on that side, into the box N, thence into the flume G, and thence out of the apparatus. In this passage of the water 80 most of the heavy particles of ore and gold will drop upon the inclined floor J and slide down the same to the front end of the box. Some of the particles of gold, &c., carried by the current will be caught on the amalgamated plates M as the water passes over the same. As the water passes over the box L 85 part of the gold, ore, &c., is caught by the sage-brush or other material in the cages O O'. A gate, as shown in dotted lines in Fig. 90 1, is placed between the guides b b of the box N on each side of the flume to prevent the water in the box on one side from passing into the box on the other. As the water accumulates in the box N and cannot pass into the 95 boxes L, it rises in the said box and flows down through the flume G, and washes out the tailings, &c., which have been dumped from the screen upon the chute Q. The gate H is slightly raised to permit the water to pass 100 through the openings or slots a and to wash out the gold, &c., which has collected in the bottom of the box F. This gold is washed upon the spout H', and is washed from the same by the water issuing from the pipes P upon 105 amalgamated plates d, as shown in Fig. 1, placed in front of the spout, to which plates the gold, &c., adheres. After the sage-brush or other material in the cages O O' has been 110 in the cages for a certain time it is removed and burned in a suitable receptacle, and the ashes are refined for the purpose of regaining the gold accumulated in the said sage-brush, &c. Part of the gold settles and collects on the 115 bottoms of the boxes, and can be removed at suitable intervals. In the manner described above the water can be conducted into the boxes F and L on either side of the screen. The water rushing through the flume G always 120 removes the tailings, whereby great labor is saved. The apparatus is so constructed that almost the entire operation is automatic, and but very little attendance is required.

The above-described apparatus is especially adapted to placer-mining; but can be used for 125 concentrating any crushed or pulverized ore.

A portion of the sand and fine worthless particles will settle in the boxes L N, and a part will be carried out of the apparatus through the flume G and the slots a in the 130 boxes F.

Having thus described my invention, what I claim as new, and desire to secure by Letters Patent, is—

1. An ore-concentrator constructed with a screen upon which the sand containing the ore is conducted, a series of settling-boxes into which the water passes after having passed through the said screen, and a flume arranged below the said screen, into which flume the water is conducted after having passed through the said settling-boxes, substantially as herein shown and described, and for the purpose set forth.
2. An ore-concentrator, consisting of a screen for the sand, &c., containing the ore, a chute for tailings at the lower or front end of said screen, settling-boxes, and a flume arranged below said screen, the front end of which flume is connected with the front end of the screen by said chute, substantially as shown and described.
3. In an ore concentrator, the combination, with a screen upon which the sand containing the gold, &c., is conducted, of an apron below the said screen, a transverse gutter at the lower end of the apron, settling-boxes at each side of and below the screen, and a flume through which the water passes after having passed from the screen and gutter into the settling-boxes and after leaving the said settling-boxes, substantially as herein shown and described, and for the purpose set forth.
4. In an ore-concentrator, the combination, with a screen upon which the sand containing the gold, &c., is conducted, of an apron below it, a transverse gutter at the lower end of the apron, settling-boxes at each side of the screen, and of a sliding gate in the said gutter for conducting the water passing into the gutter from the apron out at either end of the gutter and into the settling-boxes at one side or the other of the screen, substantially as herein shown and described, and for the purpose set forth.
5. In an ore-concentrator, the combination, with a screen upon which the sand containing the gold, &c., is conducted, an apron below the screen, and a transverse gutter at the lower end of the apron, of settling-boxes on each side of the screen, and of screens, amalgamated plates, and filter-cages in the said settling-boxes, substantially as herein shown and described, and for the purpose set forth.
6. In an ore-concentrator, the combination,
- with a screen upon which the sand containing the gold, &c., is conducted, of the boxes F, having their bottoms inclined upward from the front toward the rear end, the boxes L and 55 the gates H at the front ends of the boxes F, substantially as herein shown and described, and for the purpose set forth.
7. In an ore-concentrator, the combination, with a screen upon which the sand containing the gold, &c., is conducted, of the box F, having its bottom inclined upward from the front toward the rear end, the box L, the transverse box N, and the cages O O', containing sage-brush, grass, or other analogous filtering material, substantially as herein shown and described, and for the purpose set forth.
8. In an ore-concentrator, the combination, with a screen upon which the sand containing the gold, &c., is delivered, of the box F, having its bottom inclined upward from the front toward the rear, the box L, the box N, the gate H at the front end of the box F, and the pipe P, extending from the box N to the front end of the box F, and having its front end, P', bent 75 across the front end of the box F, the said end P' of the pipe P being perforated, substantially as herein shown and described, and for the purpose set forth.
9. In an ore-concentrator, the combination, with a screen upon which the sand containing the gold, &c., is delivered, of settling-boxes at the side of the screen, a flume arranged below the screen and adapted to receive the water that has passed through the settling-boxes, and 85 of the pipes P, extending from the rear end of the flume to the front end of the settling-boxes and across the ends of the same, which transverse parts of the pipes are perforated, substantially as herein shown and described, and for 90 the purpose set forth.
10. In an ore-concentrator, the combination, with the polygonal drums or rollers B B, of the endless screen belt A, the apron D, between the top and bottom layers of the screen, the 95 transverse gutter C, and a series of settling-boxes, substantially as herein shown and described, and for the purpose set forth.

ALEXANDER D. CLARKE.
